UNITED STATES PATENT OFFICE.

GEORGE E. MOLYNEUX, OF ELIZABETH, NEW JERSEY, ASSIGNOR TO THE SINGER
MANUFACTURING COMPANY, A CORPORATION OF NEW JERSEY.

CHAIN-STITCH SEWING-MACHINE.

1,151,528.

Specification of Letters Patent. Patented Aug. 24, 1915.

Application filed April 30, 1908. Serial No. 430,067.

To all whom it may concern:

Be it known that I, GEORGE E. MOLYNEUX, a citizen of the United States, residing at Elizabeth, in the county of Union 5 and State of New Jersey, have invented certain new and useful Improvements in Chain-Stitch Sewing-Machines, of which the following is a specification, reference being had therein to the accompanying 10 drawings.

This invention relates to an improvement in sewing machines adapted to produce chain-stitch seams, and it consists in the improvements in the looper-actuating mechanism herein shown and described.

In the accompanying drawings, Figure 1 is a side elevation, partly in section, of a "post" sewing machine embodying the present invention in its preferred form, and 20 Fig. 2 a front end view of the same with the post and the bed in section and with the face-plate removed. Fig. 3 is an end elevation and Fig. 4 a side elevation of 25 portions of the post, containing a slightly modified form of looper mechanism, and Fig. 5 a detached end view, partly in section, of the feed actuating mechanism. Fig. 6 is an end elevation and Fig. 7 a side elevation of portions of the post containing 30 another slightly modified form of the looper mechanism, and Fig. 8 a detached sectional view showing a portion of the side wall of the post with the fulcrum-stud for the looper-supporting bar represented in Fig. 7.

As shown in Figs. 1 and 2, the frame of the machine is constructed with a hollow base member 1 and tubular upright member 2 provided with the usual horizontally arranged bracket-arm 3 in which is journaled the main-shaft 4 having the balance wheel 5 and grooved belt pulley 6. The forward end of the main-shaft 4 carries the usual crank-plate 7 with crank-pin 8 embraced by one end of the pitman 9 whose 45 opposite end embraces a lateral stud 10 of a collar 11 fixed upon the needle-bar 12, herein shown provided with a multiple needle-clamp 13 carrying two spaced needles 14.

As shown in my application Ser. No.

420,533, filed March 12, 1908, the driving shaft carries a pulley 15 having a series of transverse grooves 16 and embraced by a belt 17 with clips or cross-bars 18 spaced apart correspondingly with the grooves 16 of the pulley 15, such belt embracing a similarly grooved pulley 19 secured upon the rearward end of the lower rotary shaft 20. The shaft 20 carries at its forward end the feed-actuating and lifting eccentrics 21 and 22, respectively, the looper deflecting eccentric 23 and the ball-crank 24 for communicating to the looper its loop-seizing and loop-shedding movements.

The looper is shown herein of the thread carrying type with a blade 25 having the usual thread-receiving eyes and intermediate thread groove, and the shank 26 secured within a socket in the carrier 27 loosely mounted upon the tilting looper supporting bar 28 between fixed collars 29 and adopted to oscillate thereon. The looper-carrier is provided with a ball-stud 30 embraced by a strap at the upper end of the pitman 31 whose lower end is also provided 75 with a strap which embraces the ball-crank 24 carried by the lower shaft 20, and which imparts to the looper its loop-seizing and loop-shedding movements.

The post 1^a is provided upon one side 80 with an inwardly extending hollow boss 32 in which is pivotally secured by means of the fulcrum-pin 33 one end of the looper-supporting bar 28, whose opposite end is flattened and is embraced by the spaced 85 parallel guide-ribs 34 upon the inner wall of the post opposite the boss 32. The flattened end portion of the bar 28 is embraced by and pivotally secured by means of the pin 35 within the forked head 36 of the 90 pitman-rod 37 whose opposite end is provided with a strap 38 embracing the eccentric 23 upon the shaft 20, whereby the free end of the bar 28 is vibrated so as to shift the position of the looper-blade 25 from one 95 to the other side of the needles 14, and in such manner that the looper-blade is closely adjacent to the throat-plate upon the loop-presenting side of the needle in its advance to seize the needle-thread loop and upon 100

the opposite side of the needle-path materially lower in its retrograde or loop-shedding movement.

The present looper movement, as thus described, provides for the seizure of the needle-thread loops at the highest position possible so as to permit of the employment of a short needle and correspondingly short needle-stroke, while the dip of the looper in its retrograde or loop-shedding movement 10 at the opposite side of the needle-path provides ample clearance between the throat-plate and the looper-blade for the thread-loops embracing the looper-blade and insures such an angular lead of the thread-loops to the needle-hole of the throat-plate as will insure against the premature shifting of the thread-loops along the looper-blade, thereby insuring the drawing back 15 of such thread-loops clear of the needle-path in the retreat of the looper to avoid penetration of the needle-point in the succeeding needle-thrust.

By mounting the looper-carrier intermediate the fulcrum-pin 33 at one end of the looper-bar 28 and the pivotal connection 35 with the latter's tilting means, the point of connection 30 of the pitman 31 with the carrier may be disposed sufficiently close to the looper-bar fulcrum to be comparatively little affected in its action by the needle-avoiding movements, either sidewise or endwise, thus reducing to a minimum the operative movements of the needle-carrier 35 rocking mechanism.

Opposed to the presser-foot 39 is the usual serrated feed-dog 40 mounted upon the upper end of the substantially vertical feed-bar 41 loosely fitted to slide within the fulcrum-block 42 which is secured for oscillation upon the boss 43 on one side of the inner wall of the post by means of the screw 44. As represented more particularly in Fig. 5, the feed-bar 41 is provided at its lower end with a substantially vertical yoke 45 embracing the feed-actuating eccentric 21 inclosed at the lower end by means of a cross-bar 46. To the rearward side of the cross-bar 46 is secured by means of screws 47 45 an offset horizontally arranged yoke 48 embracing the feed-lifting eccentric 22 upon the shaft 20.

As will be readily observed, the eccentric 22 communicates through the yoke 48 the 55 usual rising and falling movements to the feed-bar 41, while the eccentric 21 imparts to the feed-bar through the yoke 45 lateral movements which are reversed through the action of the fulcrum-block 42 in giving the 60 feed-dog 40 its lateral or feeding movements.

As represented herein, the feed-actuating eccentric 21 is movably mounted upon the fixed collar 49 having the adjusting screw 50 controlled by the spring-retracted turning

implement 51 substantially as in the United States Patent to Martin Hemleb, No. 809,945, of January 16, 1906. The throw of the feed-dog is therefore adjusted by varying the relation of the eccentric 21 to the supporting shaft 20.

The thread handling devices auxiliary to the needles and looper which are not specifically essentials of the present invention, are or may be of any approved style or construction.

As represented in the drawings, the looper is in retracted position and the outer end of the looper-bar elevated to throw the looper-blade in advance of the needle-path. As the shafts 4 and 20 revolve, the needle rises to 80 present its loop and the point of the looper enters the loop, the outer end of the bar 28 gradually descending to give the looper its needle avoiding movement as the point of the needle rises above the looper path. As the needle reaches its highest point, the take-up member 52 commonly carried by the needle-bar ceases to act, but the continued downward movement of the bar 28 causes the looper not only to cross the needle-path but to descend slightly beneath the throat-plate 53 so as to tighten the needle-thread loops upon the looper-blade, which is desirable especially in machines wherein a looper 85 similarly engages the loops of two needles. 90 As the looper is retracted, it carries the taut needle-thread loops backwardly to deflect them from the paths of their respective needles preparatory to the descent of the latter, after which the rise of the loops by the upward tilting of the supporting bar 28 slackens the needle-thread loops and facilitates the release of such loops preparatory to the 95 advance of the looper for a succeeding loop seizing operation.

The looper blade, and particularly the lower edge thereof, is in practice so shaped as to produce a slight drag upon the needle-thread loops hanging upon the same during its return to initial position. By the employment of a rising and falling looper the looper point is enabled to follow the needle in its up-stroke to the highest possible position beneath the throat-plate, whereby a comparatively short needle is adapted to be 115 used, which is a very important feature in sewing machines designed to operate at high speeds, while the descent of the looper during its advance movement causes its heel to be sufficiently lowered in its advance position to bring the lead of the needle-thread loops from the throat-plate under the feed-dog to establish the best conditions for proper handling of the threads. As will be observed, the dip of the looper is described 120 in producing the lateral needle avoiding movement causes the inclination of the flat looper-blade to the needle-path during the 125

retraction of the looper and descent of the needle, whereby the looper-blade is caused to perform the additional function of a needle-guard as the needles descend to enter the 5 looper-loop.

Referring to Figs. 3 and 4, the several operative parts within the post are substantially the same as already described, excepting the looper supporting bar 28 and its 10 supporting and tilting means. In this form of the improvement, the looper-bar 28' is flattened at the opposite ends, and each is embraced by the forked head 36' of a pitman-rod 37', these pitmen rods having 15 straps 38' embracing the oppositely arranged eccentrics 23' mounted upon the main-shaft intermediate the feed-actuating eccentric 21 and the looper oscillating ball-crank 24. Each of the flattened opposite 20 ends of the looper-supporting bar 28' is embraced by a pair of spaced parallel guide-ribs 34' upon the inner wall of the post, the ends of the rod 28' working in contact with curved seats 34' intermediate said guide-ribs to maintain the lateral position of the 25 looper-supporting bar. As will be observed, the bar 28' is pivotally supported by the two pitmen 37', whose reciprocal movements cause the tilting of the bar to impart the 30 needle avoiding movements to the needle, as described in connection with the form of the invention represented in Figs. 1 and 2.

In the form of the present improvement shown in Figs. 6, 7 and 8, the inner wall of 35 the casing is provided with a fulcrum-stud 54 carrying a conical headed screw-pin 55 upon which is mounted the looper-supporting-bar 28² with the looper carrier mounted upon one end portion and having the other 40 end portion flattened and embraced by the forked head 36 of the pitman rod 37 whose opposite end is provided with the strap 38 embracing the eccentric 23 upon the shaft 20, as in the form of the improvement represented in Figs. 1 and 2. The needle avoiding 45 movements in this form of the looper mechanism are produced in practically the same manner as in the preferred form previously described, and the loop-seizing and 50 loop-shedding looper movements are imparted in precisely the same manner as in the other forms before described.

In each embodiment of the improvement herein represented, the looper-supporting bar is mounted upon a fulcrum disposed beneath the throat-plate, and thus upon the farther side of the work-supporting member relative to the direction of thrust of the needle, and means are provided for confining the looper upon this supporting bar a fixed distance from said fulcrum in all of the latter's varying angular relations with the needle-path.

It will be seen from the foregoing descrip-

tion that in the several forms of the present 65 improvement disclosed herein the axis of oscillation of the looper is in substantially intersecting relation with the axis of movement of the tilting looper-supporting bar, which assumes an inclination to the path of 70 reciprocation of the needle in one direction only, never tilting from one extreme position into a position beyond perpendicular 75 relation with the vertical needle path. In the preferred form of the improvement represented in Fig. 1, the fulcrum-pin 33 is offset from the circular path in which the looper-blade oscillates a distance greater than its radius of circular movement, whereby the tilting of the bar 28 to produce 80 the sidewise or needle-avoiding movements insures the substantial rise and fall of the looper-blade as before described.

It has been common heretofore to mount the looper for oscillation upon a supporting 85 pin carried by a rocking frame fulcrumed beneath and at right angles to said pin but in such manner that the movements of said frame shifted the looper bodily from one to the other side of the needle-path without 90 producing the substantial rising and falling movements which the present improvement is designed to impart. According to the present invention, the looper is so mounted that the means whereby its sidewise movements are imparted necessarily produces its 95 above-described rising and falling movements. The looper-supporting bar is thus tilted by a direct connection with its operating means independent of the looper reciprocating mechanism in a range of movement with extreme positions within a quadrant which is limited at one side by a line coincident with or parallel to the needle-path, so that its relation with the latter 100 105 never exceeds a right angle therewith.

As will be observed by reference to Figs. 1 and 2, the post is constructed separately from the base portion 1 of the frame, and is detachably secured upon a seat provided on the latter by means of screws 56 and dowel pins 57. The object of this construction is to enable a post of one form with its contained looper and feeding movements to be 110 replaced by a post of different form for different classes of work. In order to effect such replacement, the feed-bar may readily be disengaged from the permanently mounted lower shaft and its actuating members by detaching the cross-bar 46 from the yoke 120 45, while the pitmen 31 and 37, which are provided at opposite ends with right-and-left threaded screws may be unscrewed from the fittings at their opposite ends; suitable openings being provided in practice for access to such parts.

While the looper-carrier is shown and described herein as loosely mounted upon the

tilting looper supporting bar it is evidently immaterial whether or not the looper supporting bar be made to partake of the oscillating movements of the looper-carrier, and therefore whether or not the loop-seizing and shedding movements of the looper be communicated directly or indirectly to the looper-carrier, as the characteristic feature of this improvement is the employment of 10 an endwise immovable tilting bar or member upon which the looper is mounted for oscillation.

It will be observed that in each of the 15 forms of the looper mechanisms herein shown and described the tilting movement of the looper supporting bar or member to produce the needle avoiding and rising and falling movements of the looper are in a plane parallel with the path of reciproca- 20 tion of the needle and transversely of the path of movement of the blade of the looper. The sidewise movements of the looper are performed in an arc inclined to the needle-path and upon an axis in fixed relation with 25 the latter.

Having thus set forth the nature of the invention, what I claim herein is:—

1. In a sewing machine, the combination 30 with a reciprocating eye-pointed needle, of a tilting looper-supporting bar, a rocking looper-carrier journaled upon said bar, a looper mounted in said carrier, actuating means connected with the looper-carrier for imparting to the looper endwise reciproca- 35 tory loop-seizing and -shedding movements, and means operatively connected with the looper-supporting bar and independent of the looper-actuating means for imparting to said looper-supporting bar tilting move- 40 ments upon a substantially fixed axis in sub- stantially intersecting relation with that upon which the looper-carrier performs its rocking movements and at one side of the needle-path.

45 2. In a sewing machine, the combination with a reciprocating eye-pointed needle, and a work-support, of a tilting looper-support- 50 ing bar, a fixed fulcrum passing through an extremity of said bar at one side of the needle-path and upon which said bar is confined exclusively to lateral movement in a plane parallel with the needle-path, means applied 55 to the looper-bar for imparting tilting movements thereto, a rocking looper-carrier mounted upon the looper-bar intermediate its fulcrum and its connection with said tilt- 60 ing means, a looper mounted in said carrier, and means for rocking the looper-carrier.

60 3. In a sewing machine, the combination with the frame comprising a base, an over- hanging bracket-arm and a hollow work- 65 supporting post rising from said base, of

lower and upper shafts journaled respec- 65 tively in the base and the bracket-arm, op- erative connections between said shafts, a reciprocating needle operatively connected with the upper shaft, an oscillatory looper within said post and having its blade dis- 70 posed transversely of the axis of oscillation 70 and adapted to coöperate with the needle in the production of stitches, a looper-sup- 75 porting bar arranged in the upper part of said post and upon which said looper is mounted to oscillate, means connected with 75 the lower shaft for imparting oscillatory loop-seizing and -shedding movements to the looper, and means also connected with the lower shaft for imparting to the looper- 80 supporting bar tilting movements at vary- 80 ing angles to the needle-path not exceeding a right-angle, whereby the looper-blade is given sidewise and substantial rising and falling movements.

4. In a sewing machine, the combination 85 with the frame comprising a base, an over- hanging bracket-arm and a hollow work- 90 supporting post rising from said base, of lower and upper shafts journaled respec- 90 tively in the base and the bracket-arm, op- erative connections between said shafts, a reciprocating needle operatively connected with the upper shaft, an oscillatory looper within said post and having its blade dis- 95 posed transversely of the axis of oscillation 95 and adapted to coöperate with the needle in the production of stitches, a looper-sup- 100 porting bar upon which said looper is mounted to oscillate, a transverse fulcrum-pin sup- 100 ported in the upper portion of and at one side of said post remote from the needle path and upon which said looper-support- 105 ing bar is mounted at one end, means con- 105 nected with the lower shaft for imparting oscillatory loop-seizing and -shedding move- 110 ments to the looper, and means also con- 110 nected with the lower shaft for imparting tilting movements to the looper-supporting 115 bar upon its fulcrum.

5. In a sewing machine, the combination 110 with the frame comprising a base, an over- hanging bracket-arm and a hollow work- 115 supporting post rising from said base, of lower and upper shafts journaled respec- 115 tively in the base and the bracket-arm, op- erative connections between said shafts, a reciprocating needle operatively connected with the upper shaft, an oscillatory looper within said post and having its blade dis- 120 posed transversely of the axis of oscillation 120 and adapted to coöperate with the needle in the production of stitches, a looper-sup- 125 porting bar arranged in the upper part of said post and upon which said looper is mounted to oscillate, means connected with the lower 125 shaft for imparting oscillatory loop-seizing

and -shedding movements to the looper, means also connected with the lower shaft for imparting to the looper-supporting bar tilting movements at varying angles to the needle-path not exceeding a right-angle, whereby the looper-blade is given sidewise and substantial rising and falling movements, and guiding means upon the side of said post and adapted to engage the end of

the looper supporting bar for steadyng the 10 same in performing its tilting movements.

In testimony whereof, I have signed my name to this specification, in the presence of two subscribing witnesses.

GEORGE E. MOLYNEUX.
